TUMBLER

Roland Thomas Schorer, Palos Verdes, Calif., and Morrison S. Cousins, Plainview, N.Y., assignors to Dart Industries Inc., Los Angeles, Calif.

Filed Apr. 23, 1970, Ser. No. 22,608

Term of patent 14 years

Int. Cl. D7—01

U.S. Cl. D9—220

FIG.1

FIG.2

FIG.4

FIG.3

FIG.5

FIG.6

FIG.7

FIG.9

FIG.10

FIG.8

FIG. 1 is an elevational view of a tumbler showing our new design;

FIG. 2 is a top plan view thereof;

FIG. 3 is a bottom plan view thereof;

FIG. 4 is an enlarged cross-sectional elevation view taken on line 4-4 of FIG. 2;

FIG. 5 is a fragmentary cross-sectional view taken on line 5-5 of FIG. 1;

FIG. 6 is an elevational view of a tumbler showing another form of our new design;

FIG. 7 is a top plan view thereof;

FIG. 8 is a bottom plan view thereof;

FIG. 9 is an enlarged cross-sectional elevation view taken on line 9-9 of FIG. 7; and,

FIG. 10 is a fragmentary cross-sectional view taken on line 10-10 of FIG. 6.

It is understood that the vertical ribbed pattern is continuous about the outer face of the tumbler in the path indicated by the dot-dash lines.

We claim:

The ornamental design for a tumbler, substantially as shown and described.
